UNITED STATES PATENT OFFICE.

ALBERT MARKGRAF AND HENRY BOEMERMANN, OF NEW YORK, N. Y.

GAME-COUNTER.

SPECIFICATION forming part of Letters Patent No. 617,174, dated January 3, 1899.

Application filed April 21, 1898. Serial No. 678,328. (No model.)

To all whom it may concern:

Be it known that we, ALBERT MARKGRAF and HENRY BOEMERMANN, citizens of the United States, and residents of the borough 5 of Brooklyn, county of Kings, and city and State of New York, have invented certain new and useful Improvements in Indicators for Games, of which the following is a specification.

10 This invention relates to indicators and markers used in playing games; and the object of the invention is to provide a simple device to be set up in view of players at cards to indicate the trump of the hand being 15 played, the number of the player who has the deal, and the number of rounds to be played, as agreed upon, or the number of games.

The accompanying drawings illustrate an embodiment of the invention.

20 Figure 1 is a front or face view of the indicator, and Fig. 2 is a vertical mid-section of the same. Fig. 3 shows the roller of the "rounds-indicator" detached. Fig. 4 illustrates a slightly different construction of the 25 dial and hand.

The indicator consists of a dial-head A, a base B, which rests on the table, and an upright connecting-stem C. The structure may be of any suitable material; but, as here 30 shown, it is supposed to be in the main of wood with a metal base or foot.

The dial-head, of circular form, has a recessed face covered with glass a and has a sheet-metal rim a', which may be plated and polished to present an ornamental appearance and impart a finish. On the face of the dial-head is fixed a dial a², of paper by preference, marked as follows: The dial is quartered, (see Fig. 1,) each quadrant representing a card-suit, as clubs, spades, hearts, and diamonds. In each quadrant is marked conspicuously the insignia d of the suit in the proper color (red or black) and preferably of exactly the size and contour found on the 45 common playing-card in order that the player may recognize the suit pertaining to that quadrant at a glance. About the curved margin of each quadrant are marked characters e (letters and numerals) designating the "size" 50 of the cards of a "suit," as "A" for ace, "K" for king, "Q" for queen, "J" for jack, "10" for ten-spot, &c. By preference the charac-

ters e will be printed in the color (black or red) of the suit to which they belong. In the center of the dial a² is rotatively mounted an 55 arbor g, Fig. 2, to which is fixed a hand h, adapted to traverse the dial when the arbor is rotated, and back of the dial-head a button i or similar device is fixed on the projecting end of the arbor g for convenience of 60 rotating it for setting the hand h. Above the dial on the head A is an inscription-plate a³, which has marked on it the words "Trump is" or words of like import to call attention to the significance of the position of the hand 65 on the dial.

After trump is turned by the dealer one of the players sets the hand h by means of the button i to indicate the trump—as, for example, if the king of spades is the trump 70 turned he sets the hand to "K" in the "spade-quadrant" on the dial, as indicated in Fig. 1, and the hand h remains so throughout the playing of that hand of cards, so that any player may see at a glance what the trump is. 75 The characteristic of this arrangement is that a single hand, as h, indicates at once two things—namely, the suit and size of the trump, as each quadrant contains characters e which represent all the sizes in a suit. 80

The players are usually numbered, and in some games the number is considerable. The deal passes in succession. To avoid any dispute as to who the dealer is at any time and who should succeed him, a movable indicator 85 is mounted in the upright or stem C. This "deal-indicator" consists of an endless ribbon c, mounted on two rollers c' and c². One of these rollers has fixed on its projecting journal a suitable operating-button c³, so that by rotating the roller the ribbon may be caused to travel. On the ribbon are marked in succession a series of numerals c⁴. The number of numerals in the series is not important so long as it equals the highest number of players. The number at the top is that of the dealer of the hand being played. After the hand is played, one of the players shifts the ribbon, so as to bring the next succeeding numeral to the top. The numerals appear 95 at a slot c⁵ in the front plate k.

At the bottom of the upright c is situated the indicator for the number of "rounds" to be played. This "rounds-indicator," as here

shown, consists of a roller b , having a series of numerals b' marked on in succession in a spiral form, as seen in Fig. 3, so that only one of them will appear at a time at the slot j in the front plate k . This roller b has on its projecting journal a suitable operating-button b^2 . This indicator may obviously be used to show the number of games to be played at the sitting or to count the number 10 of games that have been played.

Fig. 4 illustrates a slight modification in which the dial-card a^2 is fixed to the arbor g and rotates with it, and the hand or index h' is fixed. In Fig. 4 the device indicates that 15 the jack of spades is trumps.

It will be obvious that a strict adherence to the details of construction and arrangement shown in the drawings is not essential to the invention. Some minor changes may 20 be made without in any way departing from the invention. For example, the button i might be at the front instead of at the back and the glass a be omitted; but the glass protects the dial from dirt and dust.

25 It will be understood that while we have shown the trump-indicator constructed in the preferred form it is within this invention to provide any dial having marked on it the "suit" and "size" in proper characters and 30 any form of index or pointer to designate a particular suit and size on the dial, one of these parts being of course movable over the other.

Having thus described our invention, we 35 claim—

1. An indicator for card-games having a dial-head, a base and an upright stem, and having on its head a dial a^2 , marked as described with the suit and size arranged in 40 quadrants, and a hand or index, the said dial and hand, one of said parts being movable with reference to the other, whereby the suit and size of the trump may be indicated, substantially as set forth.

45 2. In an indicator for card-games, the combination with a support therefor, of a trump-indicator consisting of a dial a^2 , divided into

quadrants for the four suits, each quadrant having marked conspicuously on it the insignia of the suit and about its curved border 50 characters to designate all the sizes of the suit, and a single movable hand which traverses said dial, substantially as set forth.

3. In an indicator for card-games, the combination with the dial-head A, and the trump-indicator carried thereon, of the base, the stem C, and the deal-indicator in the said stem, the latter consisting of the rollers c' and c^2 , and the endless ribbon c , having on it a series of numerals c^4 , substantially as set forth. 60

4. In an indicator for card-games, the combination with the dial-head, the base, the upright connecting - stem, the trump-indicator on the dial-head, and the deal-indicator in the stem, of the rounds-indicator in the stem, 65 substantially as set forth.

5. The combination with the base and upright stem, of a dial-head A mounted on said stem, the dial a mounted in a recess in the face of said head, the glass a over said recess, 70 the inscription-plate a^3 , bearing the inscription "Trump is," the arbor g and its operating-button, and the hand h , carried by said arbor and adapted to traverse the dial a^2 , said dial being divided into quadrants and 75 each quadrant being marked with the insignia of a "suit" and with characters indicating "size," substantially as set forth.

6. In a trump - indicator for a card-game, the combination with a dial having the suit 80 and size marked on it in suitable characters arranged in a circle, and a single index to designate the suit and size of the trump turned, said parts being concentric and one movable rotatively with respect to the other. 85

In witness whereof we have hereunto signed our names, this 19th day of April, 1898, in the presence of two subscribing witnesses.

ALBERT MARKGRAF.
HENRY BOEMERMANN.
